APPARATUS AND PROCESS FOR RE-REFINING WASTE LUBRICATING OIL

George Richard Duffy, Medford, Mass., assignor to Star Oil Refining Corporation, Boston, Mass., a corporation of Arizona

Application July 21, 1933, Serial No. 681,480

4 Claims. (Cl. 196—16)

This invention relates to an apparatus and process for re-refining waste lubricating oil.

The primary object of the invention is to provide an improved apparatus and process by means 5 of which lubricating oils which have been contaminated and diluted by previous use may be refined and thereby reclaimed for subsequent lubricating use.

Another object of the invention is to provide 10 an apparatus embodying therein an improved means whereby the mixture of impure oil and clay, utilized as a bleaching agent in this process, may be agitated, circulated and preheated within the still to the end that the productive capacity of a still of a given size will be increased by reason of its greater heating efficiency.

Another object of the invention is to provide 15 an apparatus and process in which flue gases from the furnace of the still are deoxidized and utilized to produce a reducing or non-oxidizing atmosphere within the still, thereby preventing oxidation of the oil and reducing the amount of 20 clay required to bleach the oil to a given color, said gases being first subjected to a treatment 25 whereby the free O₂ is removed therefrom and then injected into the mixture of oil and clay within the still in a manner to increase the agitation thereof.

Another object of the invention is to provide 30 a means whereby the gases and products of vaporization generated within the still may be discharged therefrom and the condensable portions thereof liquefied and discarded while the gaseous or non-condensable portions thereof are united 35 with the flue gases and deoxidized in unison therewith and again injected into the mixture of oil and clay, or by-passed from the oxidizing agent and carried directly back to the still, if so desired.

Still another object of the invention is to reduce 40 the fire hazard which is usually present in this type of apparatus.

The invention consists in an apparatus and process for re-refining waste lubricating oil as 45 set forth in the following specification and particularly as pointed out in the claims thereof.

The figure of the drawing represents an apparatus embodying my invention and by means of 50 which the process of this invention is carried out.

In the drawing, 1 represents a still embodying 55 therein a horizontally disposed cylindrical container 2 for a mixture of waste lubricating oil and clay 3 mixed in suitable proportions and in a manner well-known to those skilled in the art.

The still, furthermore, embodies therein a furnace 4 provided with a stack 5 within which is a flue 6. Any suitable form of fuel may be provided for the furnace 4 and the gases generated thereby are conducted outwardly from said furnace through the flue 6.

The mixture of waste oil and clay 3 is fed into the container 2 through an inlet pipe 7. Leading from the container 2 at the bottom thereof is an outlet connection communicating with a plurality of pipes 9 suitably arranged as in a coil, or communicating one with another, and located within the furnace 4 beneath the container 2. The mixture of oil and clay is withdrawn from the container 2 and forced through the pipes 9 by means 10 of a pump 10, from which the mixture is forced back into the container through a pipe 11, said mixture being discharged below the level of the liquid within the container through a plurality of orifices 12 provided in the pipe 11. During this circulation of the mixture of oil and clay, the mixture is preheated as it passes through the pipes 9 and upon being discharged under pressure below the level of the liquid within the container 2, a 15 turbulence of the mixture is created within said container. Valves 13, 14 and 15 are provided to control the flow of liquid through the circulating means.

During the operation of the still a reducing or non-oxidizing atmosphere is maintained therein by utilizing waste flue gases that are generated by the still. To this end a pipe 16 is connected to the stack 5 in a manner to communicate with the flue 6 thereof. The pipe 16 communicates with a compressor 17 of well-known form by means 30 of which the waste flue gases are withdrawn from the flue 6 compressed and forced through a pipe 18 into a container 19 having a suitable deoxidizing agent such, for example, as pyrogallic acid contained therein.

This deoxidizing agent is so confined within the container 19 that all of the gases passing through said container will be conducted into close association therewith in such a manner that the oxidizing agent will absorb the free oxygen from the gas. The gases 35 which remain, which now contain only CO₂ and N₂ are conducted through a pipe 20 directly into the container 2 where they are discharged through a plurality of orifices 21 into the mixture of oil and clay below the surface of said mixture.

These gases are discharged under pressure into the mixture of oil and clay and the turbulence of said mixture is therefore increased. 50 A valve 22 is provided for the pipe connection 16 and valves 23 and 24 are provided for the pipe 55

connections 18 and 20 respectively. A by-pass valve 25 provides a means of intercommunication between the pipe 18 and the pipe 20 and is provided with a valve 26. By opening the valve 26 and closing the valves 23 and 24 the container 19 containing the deoxidizing agent may be eliminated from the system for reasons hereinafter to be more fully disclosed.

During the operation of the still gases and vapors are generated therein. The vapors are formed because of the presence of water and gasoline contained within the waste lubricating oil. It is necessary, therefore, to eliminate these vapors and for this purpose a pipe 27 leads from the top of the container 2 to a condenser 28 provided with a coil 29 which is exposed to a suitable cooling fluid, preferably water, which is allowed to flow through the condenser, said water entering the condenser through an inlet pipe 30 and being discharged therefrom through a discharge pipe 31. The coil 29 is connected by means of a pipe 32 to a container 33 in which the products of condensation are collected and may be withdrawn therefrom through a pipe 34 having a valve 35 provided therein. The gases which enter the container 33 are withdrawn therefrom through a pipe 36 which communicates with the pipe connection 16 leading to the compressor 17. A valve 37 is provided for the pipe connection 36. After the mixture of waste lubricating oil and clay has been treated within the still for the necessary period, the mixture is withdrawn from the container 2 and filtered by a mechanism as follows:—Connected to the pipe 11 is a pipe 38 which communicates with an agitator 39. A valve 40 is provided for the pipe 38. As the mixture of oil and clay passes through the agitator 39 a turbulence of said mixture is created therein by means of suitable paddle blades 41 provided upon a shaft 42 rotated in any suitable manner by mechanism not shown but well known to those skilled in the art. A pipe 43 connects the agitator 39 with a cooler 44 provided with a coil 45 therein through which the mixture may flow, all the time being exposed to a cooling agent, preferably water, which enters the cooler through an inlet pipe 46 and is discharged therefrom through a pipe 47. The cooler 44 is connected by means of a pipe 48 with a filter 49 of well-known construction in which is a suitable filtering medium which is adapted to separate from the oil the clay and all other foreign solid matter contained therein. The re-refined oil is withdrawn from the bottom of the filter through a pipe 50 having a valve 51 provided therein.

The general operation of the apparatus hereinbefore specifically described and by means of which the process of this invention is carried out is as follows:—Waste lubricating oil containing various types of foreign matter, together with a certain amount of clay utilized as a bleaching agent and well known in oil refining processes, is fed into the container 2 and subjected to heat provided by the furnace 4, said heat contacting directly with the under side of the container. During this heating process the liquid within the container is withdrawn therefrom by means of the pump 10 and forced through the pipes 9 which are located in the upper part of the furnace 4. As the liquid circulates through these pipes it is preheated and finally forced back into the container 2 below the level of the liquid therein in a manner to create a turbulence of said liquid within the container. The liquid is subjected to heat until the temperature thereof

ranges from 550° F. to 650° F. During this heat-treating operation waste flue gases generated within the furnace and conducted outwardly therefrom through the flue 6 are utilized as a means for maintaining a reducing or non-oxidizing atmosphere within the container 2 of the still. A portion of these waste flue gases which may contain CO₂, O₂ and N₂ are withdrawn from the flue 6 and compressed by means of the compressor 17 and discharged into contact with the deoxidizing agent which is located within the container 19, which will absorb the free O₂. The CO₂ and N₂ which remain are then forced into the container 2 and discharged therein below the level of the mixture 3 in a manner to still further increase the turbulence of said mixture. During this operation certain gases and vapors are created in the container 2 and are discharged therefrom through the pipe 27 into the condenser 28 where the products of vaporization are liquefied and finally discharged into the container 33 together with the gases which remain unliquefied. The liquid can be drawn off at any time by manipulating the valve 35. The gases are withdrawn from the container 33 by means of the compressor 17 and are compressed and deoxidized of any further free O₂ that may be contained therein in unison with the flue gases by means of the deoxidizing agent contained within the container 19, being finally discharged into a container 2 of the still as previously mentioned.

After the still has been in operation a predetermined length of time and tests disclose the fact that all of the free O₂ which is in circulation has been removed, the valve 22 is operated to cut out entirely the flue 6, thereby preventing any more waste flue gases from being placed in circulation. With all of the free O₂ removed it is no longer necessary to utilize the deoxidizing medium in the system and this is therefore cut out by closing the valves 23 and 24. The valve 26 is then opened and the gases and vapors are thereafter withdrawn from the top of the container 2 and after being conducted through the condenser 28 and container 33 to condense the vapors, the gases are forced directly back into the container 2 by means of the compressor 17 without being exposed to the deoxidizing agent. After the still has been in operation for a predetermined period at a temperature which may range between 550° F. and 650° F. the valve 15 is closed and the valve 40 opened and the liquid in a partly refined state is withdrawn from the container 2 of the still and forced by means of the pump 10 successively through the agitator 39, cooler 44 and filter 49 and the liquid is successively agitated, cooled to a certain extent, and filtered. During this filtering operation the clay and foreign solid matter that still may be contained within the oil is removed from said oil and the resulting re-refined oil may be withdrawn from the filter by manipulating the valve 51.

By closing the valves 13 and 15 the preheating operation may be cut out of the system at any time and if any leak appears in the pipes 9 the valve 13 may be actuated to prevent the oil from entering these pipes and subsequently leaking into the furnace. This construction reduces certain fire hazards that would otherwise exist. By reducing the amount of free O₂ present the fire hazard is also reduced. By utilizing waste flue gases and removing the free O₂ therefrom the expense of operating the still is greatly reduced.

By increasing both the heating efficiency and

oil velocity as said oil passes through the pre-heating tubes, a reduction in the oil film thickness is obtained. The increased velocity of the oil through the tubes 9 reduces the possibility of the oil cracking to a minimum.

5 While I have illustrated and described the waste flue gases utilized in the process of this invention as being obtained from the flue leading from the furnace to the still, it is evident that waste gases 10 may be obtained from the stack or flue of any other furnaces that may be located upon the premises adjacent to the still without departing from the spirit of this invention.

I claim:

15 1. An apparatus for re-refining waste lubricating oil comprising, in combination, a still adapted to contain a mixture of waste oil and clay, means to withdraw gases and vapors from said still and waste gases from the flue thereof, means to condense said vapors, means to deoxidize all of said gases, means to inject deoxidized gases into the still, means to cut out the flue gases, means to cut out the deoxidizing means, means to return the gases withdrawn from the still back into said 20 still to maintain a non-oxidizing atmosphere therein, and means to filter said mixture to remove the clay and other foreign matter therefrom.

25 2. An apparatus for re-refining waste lubricating oil comprising, in combination, a still adapted to contain a mixture of waste oil and clay, means to withdraw said mixture from said still, preheat the mixture and again discharge the mixture into the still below the level of the liquid therein,

means to withdraw gases and vapors from said still and waste gases from the flue thereof, means to condense said vapors, means to deoxidize all of said gases, means to inject deoxidized gases into the still, means to cut out the flue gases, 5 means to cut out the deoxidizing means, means to return the gases withdrawn from the still back into said still to maintain a non-oxidizing atmosphere therein, and means to filter said mixture to remove the clay and other foreign 10 matter therefrom.

3. The process of re-refining waste lubricating oil which consists in applying heat to a mixture of waste oil and clay, maintaining a non-oxidizing atmosphere within said mixture by passing hot 15 waste flue gases through pyrogallic acid and injecting the so-treated gases into the mixture, and finally filtering the mixture to remove the clay and other foreign particles therefrom.

4. The process of re-refining waste lubricating oil which consists in applying heat to a mixture of waste oil and clay, agitating said mixture by withdrawing the same from the mass thereof, preheating it, and then returning it under pressure into the mass below the level thereof, maintaining a non-oxidizing atmosphere within the mixture by passing hot waste flue gases through pyrogallic acid and injecting the so-treated gases, while hot, into the mixture below the level thereof, thereby increasing the turbulence of said mixture, 25 and finally filtering the mixture by removing the clay and other foreign matter therefrom.

GEORGE RICHARD DUFFY.
